US00D956855S

(12) **United States Design Patent** (10) **Patent No.:** **US D956,855 S**
(45) **Date of Patent:** **** Jul. 5, 2022**

(54) **ONE AXIS HANDHELD GIMBAL**

(71) Applicants: **Ningbo Deng**, Shenzhen (CN);
Shenghui Liao, Shenzhen (CN)

(72) Inventors: **Ningbo Deng**, Shenzhen (CN);
Shenghui Liao, Shenzhen (CN)

(**) Term: **15 Years**

(21) Appl. No.: **29/743,778**

(22) Filed: **Jul. 24, 2020**

(51) LOC (13) Cl. **16-05**

(52) U.S. Cl.

USPC **D16/243**

(57) **CLAIM**

The ornamental design for a one axis handheld gimbal, as
shown and described.

DESCRIPTION

FIG. 1 is a perspective view of a one axis handheld gimbal
showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the one axis handheld gimbal
where the one axis handheld gimbal is in a folded state.
The broken lines in the drawings depict portions of the one
axis handheld gimbal that form no part of the claimed
design.

1 Claim, 9 Drawing Sheets
